(57) **CLAIM**

The ornamental design for a portable electronic device, as shown and described.

DESCRIPTION

FIG. 1 is a front, top, and right side perspective view of a portable electronic device;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front elevational view thereof, depicted in a closed state;

FIG. 9 is a rear elevational view thereof, depicted in a closed state;

FIG. 10 is a top plan view thereof, depicted in a closed state;

FIG. 11 is a bottom plan view thereof, depicted in a closed state;

FIG. 12 is a right side elevational view thereof, depicted in a closed state;

FIG. 13 is a left side elevational view thereof, depicted in a closed state;

FIG. 14 is a front, top, and right side perspective view thereof, depicted in a closed state;

FIG. 15 is a rear, top, and right side perspective view thereof, depicted in a closed state;

FIG. 16 is a sectional view thereof, taken along line 16-16 in FIG. 2 of the portion of the bottom plan view indicated by line 1601-1601 in FIG. 5; and,

FIG. 17 is an enlarged section view thereof, taken between lines 1701-1701 and 1702-1702 in FIG. 16.

(Continued)

The broken lines in the drawings show portions of the portable electronic device that form no part of the claimed design.
